UNITED STATES PATENT OFFICE.

JOSEPH A. STEINMETZ, OF PHILADELPHIA, PENNSYLVANIA.

DEFENDING WATERWAYS.

Specification of Letters Patent. Patented Feb. 19, 1918.

1,256,741.

Application filed March 16, 1917. Serial No. 155,316.

To all whom it may concern:

Be it known that I, JOSEPH A. STEINMETZ, a citizen of the United States, and resident of Philadelphia, in the county of Philadelphia and State of Pennsylvania, have invented certain new and useful Improvements in Defending Waterways, of which the following is a specification, reference being had therein to the accompanying drawing.

My invention relates to defending coastal waterways and involves fixing in the waterway area to be protected numerous spaced receptacles containing material to be liberated when predetermined conditions arise and adapted, when discharged, to form upon the surface of the water a gaseous cloud of such character as to destroy efficient action of belligerents, either by acting directly upon the individual, or by cutting off his view, or both. For example, a gas affecting the eyes or respiratory organs is effective, or a smoke-like cloud hiding from view objects ordinarily visible may under certain conditions be equally effective and more desirable. Either renders proper fleet control, steering, sighting of guns, etc., impossible. Such attack upon the individual in affecting his eyes or his lungs in no way affects attacking a hostile vessel by the fire of guns beyond the limits of the cloud, while an opaque cloud may protect friendly shipping, for example, from attack by ships within the cloud, by aircraft above it, or by submarine below it.

The receptacles employed may be in position to be struck by any advancing vessel and provided with suitable devices whereby such contact liberates their contents, or they may be below the plane reached by such vessels and be discharged by persons at a distance, and operating preferably through known electrical devices. When contact receptacles are used, they should be located in accordance with charts provided as in the use of ordinary mines, so that a safe course may be followed by those familiar with the charts.

In the accompanying diagrammatic drawings,

Figure 1 is a plan view of a waterway provided with my devices.

Fig. 2 is a cross sectional view through the same waterway and devices.

Fig. 3 shows a receptacle with parts broken away.

In these views, A represents a channel between shores B, B, and C; C', C² fields or waterway areas in which receptacles D are spaced apart and fixed in position below the reach of moving vessels. These receptacles are connected in multiple or in series with shore batteries E, E', or the like, by electrical conductors G. The receptacles D may be of any suitable construction and each is adapted to be opened by the closing of the circuit through the corresponding station E, E', each, as shown for illustration, being provided with a small receptacle-rupturing explosive charge at D' to which the conductor G reaches. The receptacles may be filled with material, smoke producing or not, adapted to form when discharged a gaseous cloud upon and above the surface of the water the cloud being of such character that it will affect the eyes or respiratory organs of those within it, or will obstruct the view of those within or without its limits, or both. Closing a circuit at the distant corresponding station E, E' opens all the receptacles of a certain set, causes the immediate formation of a cloud which envelops any vessel or vessels H which may enter or be in the corresponding area.

Fields C' upon opposite sides of the channel may be distinct so that advantage can be taken of breezes coming from one or the other direction, and when desired a field may be connected in multiple with the shore station.

Receptacles I lying in the opposite paths of advancing vessels may be used, and several of these may be so connected that they form a multiple unit of receptacles I' each adapted to be opened by contact of a ship therewith, and the connection I² being such that rupture of one causes opening of all—as by an electric current passing from one to the other. The means employed may be any suitable well known means, for which no novelty is here claimed.

When material producing a smoke-like cloud is used, it is obvious that ships enveloped thereby are secure against aerial or submarine attack, and hence that my devices may be used to shield, directly, friendly vessels or other objects.

It is to be observed that the use of my devices does not prevent the use of ordinary mines, and furthermore that my devices can be placed in position quickly and at trifling cost even if many square miles be covered.

This is possible because the receptacles may be of any form, such as are quickly made and are largely used and carried in stock in times of peace, only very simple additions being required and no special skill or slow machine work being necessary.

What I claim is:

1. The method of defending waterways against hostile craft which consists in providing the waterway with numerous spaced and fixed receptacles arranged to discharge under predetermined conditions material adapted to form over the surface of the waterway an extensive gaseous cloud effective to prevent normal action of persons within it.
2. The method of defending waterways which consists in placing in the waterway many spaced receptacles arranged to discharge together, under predetermined conditions, large quantities of material adapted to form upon the surface of the waterway a gaseous cloud capable of preventing efficient action of persons within it, the receptacles being in known relative positions.
3. The method of defending waterways which consists in securing in the area to be protected numerous spaced receptacles containing material adapted when discharged to form above the surface of the water an extensive gaseous cloud itself adapted to prevent efficient action of persons launching from any direction an attack upon that area.
4. The method of defending waterways which consists in securing to the bottom of the waterway area to be defended numerous

spaced receptacles containing material which when discharged forms above the water's surface a gaseous cloud adapted to prevent efficient hostile action of persons attacking said area, and further providing a distant control for the discharge of said material.

5. The method of protecting waterways which consists in providing in the waterway area to be defended numerous spaced submerged receptacles discharging through electric impulse and each containing material adapted to form upon the surface of the water a gaseous cloud adapted to prevent efficient hostile action of persons within the cloud.

6. The combination with a series of spaced submerged receptacles fixed in a waterway and containing disabling gas, of electric receptacle-opening devices borne by each receptacle, and means whereby said devices may be actuated from a distant point of control.

7. The method of defending waterways which consists in providing areas on opposite sides of the channel, respectively, with submerged receptacles containing material adapted to form above the water's surface, when discharged, noxious opaque clouds, and further providing at a suitable station means for discharging said material at will upon either side of the channel.

In testimony whereof I hereunto affix my signature.

JOSEPH A. STEINMETZ.
